STACKING EQUIPMENT

David M. Wright, Shrewsbury, and Norman A. Hedstrom, Worcester, Mass., assignors to Barry Wright Corporation, Watertown, Mass., a corporation of Massachusetts

Filed July 3, 1962, Ser. No. 207,192

15 Claims. (Cl. 211—81)

The present invention relates to improvements in apparatus for the processing of business machine data cards and the like, and more particularly, to novel and improved articulated equipment promoting rapid selective stacking and withdrawal of punched cards which are circulated through high-speed card-processing machines such as sorters and collators.

Based upon convenient exploitation of the data card as a storage medium, by way of punchings, magnetic coatings and the like, various forms of business machines have been evolved to perform such important functions as encoding, storage, retrieval, compilation and computation. Inventory control, account billing, and numerous other laborious, complex and costly operations have been aided greatly by introduction of punched-card machines, as is well known. Processing speed is invariably an important factor, and accuracy is obviously essential; however, limitations in both of these respects arise out of the fact that commonly such machinery is associated with an intermediate human link which is highly susceptible to error and fatigue. By way of example, it is conventional practice for the punched cards which are being processed by certain types of business machines to be removed, stacked selectively and sequentially, and then selectively re-inserted into the machine for a further operating cycle, all through exacting manipulations by an operator. Modernly, machine processing speeds can so outstrip typical operator capabilities that wasteful and costly lags and errors can develop while the tiring operator unsuccessfully attempts to keep pace with the machine. In accordance with the present teachings, however, such difficulties are resolved through the cooperation of accessory equipment uniquely serving as a selective storage facility which may be articulated in such a manner as to ease and heighten the rate and precision of data-card manipulations by operators. For these purposes, the improved accessory equipment is preferably in the general form of a console-type truck which is convenient for the storage and transportation of standard configurations of punched cards in the very metal trays in which they are customarily held for filing, these trays being received and releasably locked into pivoted two-position counterbalanced racks which may be lodged selectively in near-vertical or near-horizontal positions which orient the cards for optimum stacking, sequential withdrawal, and transporting.

It is one of the objects of the present invention, therefore, to provide novel and improved data-card stacking equipment in which card trays may be selectively oriented to optimum positions facilitating the orderly stacking and withdrawal of cards for processing by business machines.

A further object is to provide a console-type truck for the stacking and transportation of punched cards held in common filing trays, and including provisions for tiltably adjusting and securing the trays to promote the rapid and accurate stacking and sequential removal of data cards.

Another object is to provide novel and improved stacking equipment for punched cards which is readily articulated to receive and yield up cards with ease and precision permitting high-speed processing by an operator.

2

A yet further object is to provide an accessory device, for use with punched card business machines, in the form of a console-type truck of low manufacturing cost which securely receives and selectively orients file trays of punched cards such that they may be speedily and accurately stacked and removed in orderly fashion by an operator, and such that the trays of cards may be attached, detached, articulated, transported and stored without risk of damage or spillage.

10 By way of a summary account of practice of this invention in one of its aspects, there is provided a caster-mounted open-sided console having spaced ends walls supported by a metal base framework and having a longitudinally-extending main bracket supported between them 15 at a relatively high level and about midway between the sides. Atop the main bracket are mounted a plurality of adjacent elongated racks, each of length, just short of the side-to-side width of the console, and each pivotally supported from below for tilting movements about an 20 axis extending from end-to-end of the console and disposed about midway of the lengths of the elongated racks. The racks are preferably in the form of shallow open-topped receptacles into which sheet-metal trays for the storage of punched cards may be individually nested and 25 locked with the aid of simple detent-type catches associated with the racks. Nearer one open side of the console, serving as the front at which an operator is to be stationed, each of the tiltable racks is coupled with a separate piston-cylinder shock-absorbing air cushion unit 30 of a known type which regulates the rate at which the tray supporting racks can pivot from nearly-horizontal to nearly-vertical positions under unbalanced weight of racks themselves, as well as the unbalanced weights of the card-laden trays. In their near-vertical (slightly inclined 35 toward the rear) positions, the racks support the trays in optimum orientations for rapid stacking of cards into them from the open front, while at the same time avoiding spillage. Each tiltable rack unit is further provided with a releasable catch for locking it in a near-horizontal (downwardly inclined rearwardly) position to which it 40 may be readily pivoted by the operator because of the partial counterbalancing of the rack and tray of cards about the pivot axis. In its locked near-horizontal orientation, each rack supports a tray of cards in the optimum 45 position for removal of the cards in sequence of their stacking, and for removal and loading of trays themselves, and for transportation of the trays in the rolling console.

Although the features of this invention which are considered to be novel are set forth in the appended claims, further details as to preferred practices of the invention, as well as the further objects and advantages thereof, may be most readily comprehended through reference to the following description taken in connection with the accompanying drawings, wherein:

55 FIGURE 1 presents a perspective view of an improved card stacking unit, from the front;

FIGURE 2 illustrates the same stacking unit from the rear, in perspective;

FIGURE 3 depicts a pivoted rack and card tray assembly 60, portions being broken away to expose details of locking mechanisms; and

FIGURE 4 portrays a rack and tray assembly tilted into its near-vertical orientation.

The card-stacking equipment 5 portrayed in FIGURES 65 1 and 2 includes a generally rectangular base 6 supporting upstanding end panels 7a and 7b between which extends a main support beam or mounting bracket 8 at an elevated position nearer the open top of the unit. Rigid metal framework 9 and sheet metal panelling elements 70 10 form a structure, in the nature of a console or cabinet, which is open at the top and front to expose the card stacks

11a-15a in a plurality of like card-laden file trays 11-15. Seven such open-topped trays are accommodated side-by-side in the elongated console unit, including the two further trays 16 and 17 shown only in FIGURE 2, and the front-to-back depth 18 of the console has been selected somewhat in excess of the uniform length 19 of the trays such that the latter do not project beyond the sides of the console when positioned horizontally. Typically, the trays 11-17 may comprise sheet-metal open-topped units measuring about 22½ x 6½ x 3¾ inches, with carrying bars 11b-17b exposed near their open rear ends, and with frontal lips 11c-17c disposed forwardly of recessed front panels to provide for a further hold by the operator's fingers when the separable trays are to be lifted into and out of the console. The elongated punched data cards 11a-17a stacked within such trays measure about 7¾ x 3¼ inches and are maintained in compact stacks with the aid of known forms of compressors 11d-17d slidably in internal tracks (not shown) to which they may be releasably locked at various positions as necessary.

Punched cards of the aforementioned type are coded with apertures distributed to characterize significant quantities of data with high precision, and it is therefore important that they be protected against damage, loss, or misfiling. The open trays 11-17 themselves comprise optimum filing and protective facilities, while at the same time exposing their contents so that they may be conveniently removed or augmented. Console apparatus 5 is thus advantageously constructed to accommodate these cards in the very trays in which they are normally stored, without requiring that they be separately emptied from and returned to such trays at the end of the business-machine processing served by this apparatus. For this purpose, the card trays 11-17 are received in separate elongated metal racks, 20-26, respectively, mounted side-by-side with but small spacings between them on the main cross-beam or bracket 8. The individual racks are each of open-topped shallow box-like structure, into which one of the trays may be set and held in a closely-nested relationship. Each rack may be separately locked with the tray received in it, by operator manipulation of its catch actuator (from among those numbered 20a-26a), and may be released from a near-horizontal position, to which it is automatically caught, by operator manipulation of its second catch actuator (from among those numbered 20b-26b), both actuators being disposed at the front under side of the rack. The racks are of dimensions generally complementing those of the card trays they are intended to receive, except that they may be and preferably are relatively shallow (ex. height dimension 27 may conveniently be but about 2¼ inches).

Individual mounting brackets 28-34 for the racks 20-26, respectively, are secured atop the cross-beam 8 and orient the racks at a level which corresponds to about the waist height of an operator and is therefore convenient for the lowering and raising of the trays into and out of the racks while they are locked in their near-horizontal positions. In these loading and unloading manipulations, the operator customarily grasps one of the handling lips (11c-17c) and bars (11b-17b) at opposite ends of the tray to hold and guide it properly. For reasons concerned with optimum manipulations in removal of groups of punched cards from the trays, such that they may then be fed to a business machine in proper sequence, the trays are preferably locked to have a slight downward inclination, rearwardly, rather than to be locked in the strictly level or horizontal position. Were the latter true, loose stacks of punched cards would tend to fall flat in the trays, where they would be difficult to remove quickly or where they might be overlooked and thereby disrupt the needed sequential removal operation. However, the illustrated downward inclination of the trays insures that the cards will tilt toward the rear and remain stacked in the sequence originally given them, such that they may then be withdrawn in proper sequence also. One suitable mecha-

nism for the near-horizontal locking is in the nature of a releasable spring-biased detent which is part of the bracket supporting the rack, this being shown in FIGURE 3 and described in detail later herein, although it will be apparent that other latching or releasable locking constructions may be exploited instead.

While the near-horizontal orientations of the racks (and, hence, the trays) are important for the loading and card-removal operations already referred to, the stacking of punched cards into these trays cannot be performed speedily while they are so oriented. For the latter purposes, the trays should be very nearly vertical, whereby the operator may then resort to highly convenient and accurate downward flipping motions in successively pocketing small stacks of cards in the trays. The tray racks 20-26 are therefore individually pivoted, on their respective support brackets 28-34, about a common longitudinal axis 35-35 which extends transversely below the elongated racks about mid-way of their lengths. Each rack is somewhat counterbalanced about the pivot axis even when heavily laden with the cards in a mated tray, such that the operator experiences little difficulty in turning a tray from vertical to horizontal. However, a mass unbalance favoring the vertical orientation is developed intentionally, whereby even an unloaded rack will tend to gravitate toward the front. When card-loaded trays are carried by the racks, they tend to drop forcefully and quickly to their near-vertical orientations, such as those illustrated for trays 11-13 in FIGURE 1, and were it not for two preventive features there would be serious risk that the punched cards would be spilled. Such spillage, and consequent loss, damage, or disruption of sequence, are avoided by the cushioning devices 36-41 which dampen the permissible rates of forward tilting, and by bracket surfaces which engage to serve as stops preventing the trays from quite reaching the vertical. As illustrated in FIGURE 1, the forwardly-tilted racks and trays are inclined rearwardly, from bottom to top, and the punched cards thus tend to remain securely in their stacked positions. Preferably, the damping devices 36-41 are of a known simple air-cushion type such as are commonly used to regulate door closures, the damping effect in one direction being adjustable by manipulation of an air-bleed valve which controls the rate at which the air compressed by a movable piston may escape from the surrounding cylinder, and the restraints in the opposite direction being negligible. Other forms of dampers may obviously be exploited also.

Details of one rack and tray assembly are exposed in the FIGURE 3 illustration of the rack 24 into which the tray 15 has been nested and locked to accommodate the punched cards 15a. The overlapping sides 24c and the floor 24d of the rack 24 form a shallow box-like receptacle fitting closely with tray 15. Locking, which is important in preventing separation of the tray and rack during the permitted tilting movements, is provided in part by a fixed rear catch in the form of a tongue 43 projecting forward from the rear end of the rack slightly above the floor 24d such that the floor 15e at the rear open end of the tray may be trapped in place. At the front end, the lower forwardly-extending edge 15f of the tray is releasably held by a slideable catch 44 which is normally held in the illustrated rearmost position by a spring 45 but which may be pulled forward with the attached downwardly-extending release handle 24a to disengage itself from the tray. The latter may then be readily withdrawn from the rack.

Support bracket 32 includes a member 32a affixed to and movable with rack 24, a member 32b fixed with the movable rack and having a forked coupling 32c for pivotal connection with the end of piston rod 46 of the air-cushion unit 40, and a stationary bracket member 32d mounted atop the cross-beam support 8. As is shown in FIGURE 1, bracket member 32d is generally U-shaped, and a pivot pin 47 extending between its spaced upstanding sides supports the upper bracket part 32b (and the affixed rack).

for the desired tilting movements about the axis 35—35. At their rear edges, the sides of bracket member 32d are each shaped to form a detent slot or notch, 48, into which the ends of a detent in the form of a locking pin 49 may be caught to prevent relative tilting motion between the rack and frame-work member 8 when the rack is in the illustrated near-horizontal orientation (i.e., with its rear end downwardly inclined by the small angular amount 50, which may conveniently be of the order of 10 degrees). Locking pin 49 is fixed with a pivoted plate 51 which is angularly movable relative to the bracket member 32a on which it is pivoted by a support shaft 52. Release spring 53, coupled between pins 47 and 49, biases the latter into locking engagement in the notch 48 when the rack 24 is properly oriented; however, the force of this spring may be overcome, and the locking pin 49 may be disengaged, by operator manipulation of the downwardly-extending slide handle 24b. This handle is affixed to a slide bar 24e, the rear end of which possesses a tongue coupled with the pivoted plate 51, when the handle is pulled forward by the operator, slide bar 24e pivots plate 51 about shaft 52, causing the locking pin to leave notch 48, such that the somewhat unbalanced weight of the cards 15a will cause the rack and tray to tilt clockwise (FIGURE 3). Release of handle 24b permits spring 53 to bias pin 49 into engagement with the camming surfaces 32e of bracket member 32d, on which surfaces the pin rides freely without locking unless in position to drop into notch 48. Tilting of the rack and tray is damped by the air-cushion unit 40, and when the tray is fully tilted to the near-vertical orientation the rubber shock bumper or stop 54 on the lower edge of bracket member 32b engages the forward edge or stop of cross-beam 8 to halt further tilting. The latter orientation is depicted in FIGURE 4, wherein the tray and rack angular inclinations 55 from the vertical are of the order of about 15 degrees.

The console-type unit as a whole is movable on casters, 56, and is provided with rail handles 57, FIGURES 1 and 2, for convenience of the operator in adjusting the position of the stacking console in relation to a card-processing business machine with which it is to be used. In practice, the empty racks 20—26 are locked in the near-horizontal position by pin 49 engaging slot 48 in mounting bracket 32d and are loaded from above with trays which may be empty or may contain cards which are to be processed. Commonly, one of the trays, such as the right-most tray 15 is left empty at the start, and it is dropped to the near-vertical position for first filling by the operator as the cards which have been fed to the associated business machine are recovered in a predetermined sequence. The operator finds it most convenient to have the trays from which the cards are being removed locked in the near-horizontal position, but these are dropped to the near-vertical position when emptied or otherwise readied to receive stacks of cards from the operator. As is evident from the illustration in FIGURE 1, the racks and trays which may be in a near-horizontal position are so oriented that they do not project materially forward of those trays which are in the near-vertical positions, and thus do not obstruct stacking of cards into the latter trays. Once a tray is properly stacked, the operator may tilt it backward with ease about axis 35—35 until the locking pin and detent provisions stop and hold it in the near-horizontal position desired for removal of cards or transportation of the loaded trays in the truck.

In alternative constructions, the tiltable racks may of course be mounted on a common shaft, rather than on separate brackets and pivots, although the latter feature provides a desired flexibility in manufacture of units for handling different numbers of trays. Similarly, while air-cushion devices have been described in association with the tiltable racks, other equivalent dampers, such as those which are frictional or hydraulic in character, may be substituted. In addition, the provisions for locking the trays onto the racks, and the racks to the console

framework when they are in the near-horizontal positions, may assume forms which are structurally different from those described. The term "card" as used herein is intended to apply not only to punched but magnetically-coded cards and sheets as well, and to items, such as checks, which are functionally similar insofar as processing and handling are concerned. Accordingly, while specific practices have been discussed, and while preferred embodiments have been shown and described, it should be understood that various changes, modifications, additions and substitutions may be effected by those skilled in the art without departure from these teachings, and it is aimed in the appended claims to embrace all such variations as fall within the true spirit and scope of this invention.

15 What we claim as new and desire to secure by Letters Patent of the United States is:

1. Card-stacking apparatus for supporting a plurality of elongated card trays in preferred positions for stacking and removal, comprising a framework, a plurality of elongated card trays, a plurality of racks each including means releasably locking one of said card trays thereon, means supporting said racks in side-by-side relationship on said framework for independent pivotal movements about an axis, means for releasably locking each of said racks to said framework in first angular orientations about said axis wherein said racks position said trays locked thereon substantially horizontally, and stop means limiting angular movements of said racks between said first angular orientations and second angular orientations wherein said racks position said trays locked thereon substantially vertically, whereby cards may be readily stacked in and removed from said trays when said racks position said trays substantially vertically and horizontally, respectively.

2. Card-stacking apparatus for supporting a plurality of elongated card trays in preferred positions for stacking and removal, comprising a framework open at the top and front, a plurality of elongated card trays, a plurality of racks each including means releasably locking one of said card trays thereon, means supporting said racks in elevated positions on said framework for independent pivotal movements about a horizontal axis disposed rearwardly of the front of said framework, means for releasably locking each of said racks to said framework in first angular orientations about said axis wherein said racks position said trays locked thereon substantially horizontally with said trays exposed at the top of said framework, and stop means limiting angular movements of said racks between said first angular orientations and second angular orientations about said axis wherein said racks position said trays locked thereon substantially vertically with said trays exposed at the front of said framework.

3. Card-stacking apparatus for supporting a plurality of elongated open-topped card trays in preferred positions for stacking and removal, comprising a console framework having a base and at least two upstanding spaced sides, said framework being open at the top and front, a plurality of elongated open-topped card trays, a plurality of racks each including means releasably locking one of said card trays thereon, means supporting said racks in elevated positions on said framework for independent pivotal movements about a horizontal axis disposed rearwardly to the front of said framework and perpendicularly to said upstanding sides, means for releasably locking each of said racks to said framework in first angular orientations about said axis wherein said racks position said trays locked thereon substantially horizontally with the open tops of said trays exposed at the open top of said framework, and stop means limiting angular movements of said racks between said first angular orientations and second angular orientations wherein said racks position said trays locked thereon substantially vertically with the open tops of said trays exposed at the open front of said framework.

4. Card-stacking apparatus for supporting a plurality of card trays in preferred positions for stacking and re-

moval, comprising a framework open at the top and front, a plurality of elongated card trays, a plurality of racks each including means releasably locking one of said elongated card trays thereon, means supporting said racks in side-by-side relationship on said framework for independent pivotal movements about an axis, means for releasably locking each of said racks to said framework in first angular orientations about said axis wherein said racks position said elongated trays locked thereon in near-horizontal positions with slight downward inclinations away from the front of said framework, and stop means limiting angular movements of said racks between said first angular orientations and second angular orientations about said axis wherein said racks position said trays locked thereon in near-vertical positions and expose said trays at the front of said framework with slight rearward inclinations in direction from bottom to top of said framework.

5. Card-stacking apparatus for supporting a plurality of card trays in preferred positions for stacking and removal, comprising a framework open at the top and front, a plurality of elongated card trays, a plurality of racks each including means releasably locking one of said elongated card trays thereon, means supporting said racks in side-by-side relationship on said framework for independent pivotal movements about a horizontal axis disposed rearwardly of the front of said framework, means for releasably locking each of said racks to said framework in first positions wherein said racks position said elongated trays locked thereon substantially horizontal, said supporting means supporting said racks for gravitationally-induced pivotal movements from said first positions to second positions wherein said racks position said elongated trays locked thereon substantially vertical, and stop means limiting pivotal movements of said racks short of the angles at which said trays locked thereon are vertical.

6. Card-stacking apparatus for supporting a plurality of open-topped card trays in preferred positions for stacking, removal, transportation or storage, comprising a framework open at the top and front, a plurality of elongated open-topped card trays, a plurality of racks each including means releasably locking one of said elongated card trays thereon, means supporting said racks in side-by-side relationship on said framework for independent pivotal movement about a horizontal axis disposed rearwardly of the front of said framework below the level of said trays locked on said racks and transversely in relation to said elongated trays, means for releasably locking each of said racks to said framework in first positions wherein said racks position said elongated trays locked thereon substantially horizontal, said supporting means supporting said racks and said trays locked thereon in unbalanced relationship about said axis to induce the front end of each of said elongated trays to tilt downwardly from the substantially horizontal position upon release of the locking means locking its rack to said framework, and stop means limiting the downward tilting of said racks and said trays short of but near the angles at which said trays locked on said racks are vertical.

7. Card-stacking apparatus for supporting a plurality of open-topped card trays in preferred positions for stacking and removal, as set forth in claim 6, wherein said axis is disposed transversely in relation to said trays locked on said racks at a position intermediate the ends of said trays wherein the mass of the racks and of said trays locked thereon is greater to the side of said axis nearer the front of said framework than to the side nearer the rear of said framework, whereby the racks and said trays locked thereon are partly counterbalanced about said axis while nevertheless remaining unbalanced and tending to remain downwardly tilted.

8. Card-stacking apparatus for supporting a plurality of open-topped card trays in preferred positions for stacking and removal, as set forth in claim 7, wherein said means for releasably locking said racks to said framework

5. lock said racks in first positions wherein said racks position said trays locked thereon slightly inclined downwardly away from the front of said framework and wherein the unbalanced mass of the racks and of said trays locked thereon nevertheless tends to tilt the fronts of the racks and said trays downwardly at the front of said framework, and wherein said stop means limits said downward tilting to angles at which said racks position said trays locked on said racks slightly inclined rearwardly from bottom to top of said framework to prevent spillage of cards from the open-topped trays.

10. 9. Card-stacking apparatus for supporting a plurality of open-topped card trays in preferred positions for stacking and removal, as set forth in claim 6, further comprising a plurality of damping units connected between said framework and each of said racks and damping said downward tilting of said racks and said trays locked thereon.

15. 10. Card-stacking apparatus for supporting a plurality of open-topped card trays in preferred positions for stacking and removal, as set forth in claim 9, wherein each of said damping units comprises an air-cushion damper having a relatively movable cylinder and piston connected between one of said racks and said framework.

20. 11. Card-stacking apparatus for supporting a plurality of open-topped card trays in preferred positions for stacking and removal, comprising a framework open at the top and front, a plurality of elongated open-topped card trays, a plurality of racks each including means releasably locking one of said elongated card tray thereon, means supporting said racks in side-by-side relationship on said framework for independent pivotal movements about a horizontal axis disposed rearwardly of the front of said framework at an elevated position, means for releasably locking each of said racks to said framework in first angular orientations about said axis wherein said racks position said open-topped trays locked thereon substantially horizontally and with said trays exposed at the top of said framework, stops means limiting angular movements of said racks between said first angular orientations and second angular orientations about said axis wherein said racks position said open-topped trays locked thereon substantially vertically and with said trays exposed at the front of said framework, and a plurality of damper units each connected with a different one of said racks and with said framework and damping the pivotal movements of said racks and said trays from the substantially horizontal to the substantially vertical positions.

25. 12. Card-stacking apparatus for supporting a plurality of open-topped card trays in preferred positions for stacking and removal, comprising a framework open at the top and front, a plurality of elongated open-topped trays, a plurality of elongated open-topped racks each shaped to receive and nest about the base of one of said elongated open-topped card trays and including means releasably locking one of said card trays thereon, a plurality of bracket means mounted on said framework and each independently supporting a different one of said racks for pivotal movements about a horizontal axis disposed rearwardly of the front of said framework at an elevated position, means for releasably locking each of said racks to said framework in first positions wherein said elongated racks are substantially horizontal, and stop means limiting pivotal movements of said racks on said bracket means short of the angles at which said elongated racks are vertical and opened toward the front of said framework.

30. 13. Card-stacking apparatus for supporting a plurality of open-topped card trays in preferred positions for stacking and removal, as set forth in claim 12, wherein said bracket means support said elongated racks in side-by-side relationship, and wherein each of said bracket means pivots a different one of said racks about an axis below the rack and in an unbalanced relationship which induces the front end of the rack to tilt down-

wardly from the substantially horizontal position upon release of the means locking it to said framework.

14. Card-stacking apparatus for supporting a plurality of open-topped card trays in preferred positions for stacking and removal, as set forth in claim 13, wherein each of said bracket means comprises a first bracket member secured to the under side of a rack, a second bracket member mounted on said framework, means pivoting said first bracket member on said second bracket member about said axis, a movable detent member mounted on said first bracket member, said second bracket member having surfaces forming a detent notch disposed to engage and lock with said detent member when the rack fixed with said first bracket member is substantially horizontal, and means mounted on said bracket means resiliently urging said detent member into said detent notch, and wherein said means for releasably locking each of said racks to said framework includes a manually-movable member mounted below the rack at the front end thereof, and means connecting said movable member with said detent member to move said detent member out of said detent notch.

15. Card-stacking apparatus for supporting a plurality of open-topped card trays in preferred positions for stacking and removal, as set forth in claim 14, wherein each of said elongated trays has front and rear bottom edges, wherein said means releasably locking one of said card trays on each of said open-topped racks comprises a fixed catch at the rear of each of said racks disposed

5 to engage and trap the rear bottom edge of the one of said card trays nested therewith, and a movable catch at the front end of each of said racks disposed to slide into and out of trapping engagement with the front bottom edge of the one of said card trays nested therewith, 10 a second manually-movable member mounted below each of said racks at the front end thereof, means connecting said second movable member with said movable catch of each of said racks to move said movable catch thereof out of engagement with the front bottom edge of the one of said trays nested therewith, and means resiliently urging said movable catch of each of said racks into trapping engagement with the front bottom edge of the one of said trays nested therewith.
